B. A. SMITH ET AL

OXYGEN APPARATUS

Filed Feb. 15, 1919

UNITED STATES PATENT OFFICE.

BENJAMIN A. SMITH, OF LAKEWOOD, OHIO, AND WILLIAM G. KEAT, OF PEN ARGYL,
PENNSYLVANIA.

OXYGEN APPARATUS.

Application filed February 15, 1919. Serial No. 277,337.

To all whom it may concern:

Be it known that we, BENJAMIN A. SMITH and WILLIAM G. KEAT, both citizens of the United States, residing at Lakewood, Ohio, and Pen Argyl, Pennsylvania, respectively, have invented certain new and useful Improvements in Oxygen Apparatus, of which the following is a specification.

This invention relates to apparatus for supplying oxygen to aviators and others in locations where oxygen is insufficient. For instance, the apparatus of this invention may be used to provide oxygen to aviators at great altitudes. The apparatus may also be used to provide oxygen to persons who are in atmospheres which are deficient in oxygen by reason of foulness of the air, or the presence of noxious gases.

More particularly, the invention relates to a pressure reducing mechanism for use in connection with such apparatus.

It is well known that various forms of apparatus have been used for airplane service which were automatic in their operation so far as variations in pressure due to altitude and consequent variations in the amount of oxygen per cubic foot of air were present. All of these forms of apparatus before known have been open to very serious objections that temperature changes markedly affected the pressure reducing mechanism commonly used to step down the oxygen pressure from a high storage pressure to a breathable pressure. This defect has been due to the fact that the forms used were not thermostatically neutral. It is also well known that the temperature at a given time at the earth's surface is much greater than the temperature at the same time several thousand feet above the point chosen on the earth's surface as a datum point for the measurement of such temperature.

The principal and most important object of the invention is, therefore, to provide a form of pressure reducing mechanism which will be thermostatically neutral, and so deliver the proper amount of oxygen to the user regardless of the surrounding temperature.

It is also well known that it is sometimes necessary, especially in the larger airplanes, to provide one person or several persons, with oxygen. Furthermore, it is necessary to vary the amount of oxygen so provided

in accordance with the rarefaction of the air.

A second object of the invention is to provide an improved form of valve for controlling the supply of oxygen so that one or more persons may be supplied with the proper quantity of oxygen in an improved manner at various altitudes.

With the above and other objects in view as will hereinafter be apparent, the invention consists in general of certain novel details of construction and combination and arrangement of parts hereinafter fully described and illustrated in the accompanying drawings and specifically claimed.

In the accompanying drawings in which like characters of reference indicate like parts in the several views,

Fig. 1 is a front elevation of the device as it appears on the instrument board of an airplane.

Fig. 2 is a bottom plan thereof.

Fig. 3 is a section on the line 3—3 of Fig. 1.

Fig. 4 is a section on the line 4—4 of Fig. 1.

Fig. 5 is an enlarged detail section through the flow indicator.

Fig. 6 is a section on the line 6—6 of Fig. 4.

Fig. 7 is a section on the line 7—7 of Fig. 4.

Fig. 8 is a broken plan view of Fig. 1.

In carrying out the objects of this invention there is provided a base 10 on which the various parts of the apparatus are assembled.

Considering now the pressure reducing apparatus: On this base 10 there is secured a suitable casing 11, which is held in position on the casing by the screw 12 and lock-nut 13. In the base 10 is an opening 14, through which extends a threaded nib 15, having a screw slot 16 in its lower end. The upper or inner end of this nib 15 is securely soldered or otherwise fastened to the lower side of a corrugated aneroid shell 17 between which and the bottom of the casing 11 is a washer 18. On the lower end of the nib 15 is a nut 19 forming a locknut. Now from the foregoing, it will be seen that when the nut 19 is rotated so as to compress the washer 18 between the shell 17 and the lower side of the casing 11, an air-tight joint is

formed. Within the casing 11 is located a U-shaped yoke 20 between the arms of which extends a pin 21 whereon is pivoted the angular portion of a bell crank lever 22. One arm of this bell crank 22 extends over the aneroid shell 17, and on a pin 23 carried by this arm is pivoted a threaded sleeve 24. Screwed into the threaded sleeve 24 is a nib 25 which is coaxial with the nib 15 and which is likewise fixed securely to the aneroid shell 17. Usual springs 17' are located in the box 17. Now, it will be observed, that the position of the aneroid shell relative to the overhanging arm of the bell crank 22 may be moved at will to suit the varying conditions by rotating the shell and nibs through the instrumentality of a screwdriver engaging the slot 16, the locknut 19 being loosened for this purpose. The reason of the desirability of this adjustment will presently appear.

Extending laterally from the casing 11 is a boss 26 wherein is mounted a sleeve 27 having a minute opening 28 therein which terminates in a valve seat 29. This valve seat 29 is engageable by a valve 30 made of bakelite or analogous material carried by the bell crank lever 22 on the arm thereof which extends over the valve seat. A valve seat of bakelite is found to be particularly satisfactory, for two reasons:—it is not corroded by the oxygen, and it is slightly softer than the valve seat 29, whereby any irregularities in the valve seat will indent the bakelite to give a tight seal. Fixed to the base 10 by means of the screws 31 is a boss 32 which is threaded exteriorly to receive the connections from a high pressure tank containing oxygen, the tank not being here shown. In the boss 26 is formed a seat 33 wherein extends the outer end of the boss 26, a compression washer 34 being held between said outer end and the valve seat 29, the valve seat 29 being held securely in position by means of solder or the like. Through the boss 32 extends a passage 35 which communicates with the passage 36 terminating in an offset portion 37 communicating with the opening 28 in the valve seat 29.

An extremely important feature of the invention resides in the fact that the aneroid shell 17 has the air normally contained therein exhausted so that the interior pressure is about one millimeter of mercury, although this pressure may vary in accordance with the conditions obtained in the remainder of the apparatus.

Now upon the opening of this part of the device oxygen will be admitted through passage 36 and by reason of the pressure obtained, the valve 30 will open and in consequence will build up within the casing 11 a pressure which will operate to compress the sides of the aneroid shell 17 and move them toward each other. This in turn will rock

the lever 22 and will move the valve 30 to engage the seat 29 and thereby shut off further flow of the oxygen through the opening in the boss 32.

Extending from one side of the casing 11 is a tube 38 through which the oxygen to be used passes to the user. Now as soon as any oxygen passes through the tube 38, the pressure within the casing falls, the aneroid shell 17 expands, and the valve 30 is again moved away from its seat to allow further oxygen to enter the casing 11. The inrushing gas again shuts the valve 30 and as this operation is repeated so long as oxygen is passing through the tube 38 the pressure is kept down to the required degree. During this operation the valve can be heard opening and closing similarly to the ticking of a watch, only much more rapidly. In other words, the valve action is intermittent.

It now becomes apparent that the pressure within the casing 11 can be varied at will by adjustment of the nib 25 in the sleeve 24 and that by such adjustment the differences in pressure necessary to open and close the inlet valve may be regulated to suit the prevalent conditions.

In the ordinary form of the device employing an aneroid shell the aneroid shell is not exhausted and while the device set for a given temperature may function properly under varying conditions of pressure, yet a variation in the temperature will affect the contents of the shell so that when the temperature rises a greater pressure within the casing 11 before the valve 30 closes and, when the temperature falls, the pressure within the shell decreases thus decreasing the pressure necessary in the casing 11 to close the valve. Supposing the device is used in connection with an airplane and that it is so adjusted as to operate at the temperature of the air near the earth's surface. As the airplane ascends both the temperature and the pressure of the air decrease so that the higher the altitude, the more necessary it is to obtain a supply of oxygen through the instrument. However, since the pressure within the shell in former instruments decreases with the temperature the valve 30 was more readily closed and consequently the amount of oxygen flowing through the casing 11 decreased. In the present instance, the remaining pressure within the aneroid shell 17 is just sufficient that the effect of the temperature on this remaining gas just compensates the temperature effect of the metal of the shell and the consequence is that the device is thermostatically neutral.

For the purpose of observing the pressure within the passage 36 the boss 32 is provided with a lug 39 having a suitable opening therethrough which communicates with a Bourdon tube 40 mounted within a casing 41 and operating the usual pointer 42 travers-

ing a scale 42', thus constituting a pressure guage.

Considering now the distributing valve for the oxygen which leaves the pressure reducing mechanism heretofore described. Mounted on the base 10 by means of screws 43 is a cylindrical casing 44 within which is mounted a rotary sleeve 45 wherethrough extends a plurality of slots 46. The slots 46 communicate with tapered circumferential slots 46'.

In the casing 44 is screwed a head 47 whereto the pipe 38 from the pressure reducing device is connected by a suitable compression joint 48. The other end of the casing 44 is closed by a combined sleeve and cover 49 which holds the valve sleeve 45 in place and is provided with an outwardly extending hollow boss 50 wherethrough passes a stem 51 having pivoted on its inner end a cross bar 52, the ends whereof fit in slots 53 in one end of the sleeve 45. By means of this arrangement any eccentricity of the stem 51 relative to the sleeve valve 45 is compensated.

Fixed on the outer end of the stem 51 is a rock arm 54 to which is connected an adjusting screw 55 slotted at its end. Between the ends of the slotted ends of the screw 55 is pivoted a stem 56 which is connected to one of a series of aneroid cells 57, the other end of the series being fixed to a support 58 by means of a threaded stem 59 provided with adjusting nuts 60. The threaded stem 59 permits adjustment of the sleeve 45 so that the valve openings 46 may be set as desired.

The remaining cylindrical portion of the casing 44 is closed at one end by a head 62 to which is soldered a tube 63 forming the efflux tube from this portion of the apparatus. To afford communication between the interior of the sleeve 45 and the interior of the portion of the casing 44 communicating with the tube 63, this being preferably termed the chamber 64, there is provided a pair of ports 65 and 66. Rotatably mounted within the chamber 64 is a cylindrical valve 67 preferably slightly tapered in form to form a plug valve. This valve 67 has a centrally transposed opening 68 wherewith communicate laterally extended openings 69 arranged preferably at an angle of 180° to each other. The openings 69 may be brought into register with respective ports 65 and 66 by rotating of the valve 67 manually.

In order to hold this valve in position, there is provided a closing plug 70 between which and the valve is located a compressor spring 71, the stem 72 of the valve extending outward as shown. Connected to the stem 72 in such manner as to effect rotation thereof, is a tube 73 carrying on its end a finger operated pointer 74 whereby the valve 67 may be rotated at will so that either port 65 or 66 may be opened or both be closed.

It is necessary that the user of the apparatus be at all times informed whether the oxygen is flowing properly through the device or not, and to this end there is provided a casing 75 having extended therefrom a pipe connection 76. This pipe connection is for the purpose of receiving one end of the tube whereby the device may be connected to the usual aviator's mask. The pipe 63 communicates with this casing and on the interior of the casing is an arcuate pipe 77 having a series of upwardly directed openings 78 therein. This arcuate pipe 77 communicates directly with the pipe 63 so that any oxygen passing through the pipe 63 will be directed upwardly in the casing through the openings 78. At the top of the casing 75 is a yoke 79 and in the yoke 79 and bottom of the casing 75 are alined jewelled bearings 80 wherein are mounted the ends of a staff 81 carrying a propeller fan 82 and a disc 83. The disc 83 is preferably painted black or may be processed to form a black surface and on this disc is a spiral line 84 of luminous paint, so that rotation of the disc 83 is visually indicated both day and night. The casing 75 is preferably covered by a suitable glass 85, with a bezel connection 86 to the casing.

The operation is as follows: High pressure oxygen enters the passage 36, travels through the small passage 28 to the interior of the casing 11 to fill it with oxygen and to increase the pressure there until the valve 30 closes. From the casing 11, the oxygen passes, by pipe 38, to the distributing valve 44, tending to lower the pressure in the casing. As soon as the pressure falls below a certain point, the aneroid will open the valve 30 to let in more oxygen, so that a substantially constant pressure of oxygen will be maintained in the casing 11.

The oxygen passes into the pipe 38 and thence to the distributing valve shown in Fig. 4. From the interior of the sleeve 45 the oxygen passes through one of the ports 46 and its associated tapered slot 46'. The oxygen passes through port 46, into the tapered slot 46' and travels along this slot until it reaches the point where one of the ports 65 or 66 opens into slot 46'. After passing through port 65 or 66, the oxygen passes into one of the passages 69 and thence into pipe 63, then through pipe 63 to the flow indicator 75, where it causes rotation of the fan 82 and disk 83; the oxygen then passes out pipe 76 to the breathing mask of the aviator. Valve 69 may obviously be set to completely cut off all oxygen flow.

It will be noted two tapered slots 46' are provided, either one or the other of which may be put in action, by turning the valve 69, by handle 74, to bring either port 65 or 66 into communication with one or the other slots 46'. The purpose of having two slots

46' is to adapt the apparatus for delivering oxygen to one, or two, aviators. Additional slots could, of course, be provided, to supply sufficient oxygen to any desired number of 5 aviators and such a modification falls within the scope of the invention.

The tapered slots 46' may be of several possible cross-sections, as long as they decrease gradually in cross-sectional area. 10 The cross-sectional area of the slot for two aviators will obviously be somewhat larger than the slot intended for use with one aviator.

It should be understood that the several 15 features of our invention are capable of being carried out in other ways and that accordingly the invention be not limited to the precise embodiments here shown by way of illustration.

20 We claim:—

1. A pressure responsive element of the aneroid type comprising a shell from which the air has been exhausted to such a de-

gree as to render the element substantially independent of temperature changes within 25 the shell.

2. A pressure responsive element of the aneroid type embodying a shell from which the air has been exhausted to such a degree that changes in conformation of the material of the shell due to expansion and contraction are rendered substantially independent of temperature changes outside of the shell. 30

3. A pressure responsive element of the aneroid type, comprising a shell exhausted to such a partial vacuum, that changes in the material of the shell due to expansion and contraction are rendered substantially independent of temperature changes outside 40 of the shell so that a substantially thermostatically neutral combination is obtained. 35

In testimony whereof we have affixed our signatures.

BENJAMIN A. SMITH.
WILLIAM G. KEAT.
